US0D1084819S

(12) **United States Design Patent** (10) Patent No.: **US D1,084,819 S**
(45) Date of Patent: ** Jul. 22, 2025

(54) **ELECTRONIC LOCK**

(71) Applicant: **TONG LUNG METAL INDUSTRY CO., LTD.**, Minxiong Township, Chiayi County (TW)

(72) Inventors: **Ju-Lin Yang**, Minxiong Township, Chiayi County (TW); **Jui-Chieh Cheng**, Jhuci Township, Chiayi County (TW); **Yu Lin**, Chiayi (TW)

(73) Assignee: **TONG LUNG METAL INDUSTRY CO., LTD.**, Minxiong Township, Chiayi County (TW)

(**) Term: **15 Years**

(21) Appl. No.: **29/918,248**

(22) Filed: **Nov. 27, 2023**

(30) **Foreign Application Priority Data**

Jun. 30, 2023 (TW) 112301016D01

(51) LOC (15) Cl. **08-07**

(52) U.S. Cl.

USPC **D8/331**

(57) **CLAIM**

The ornamental design for an electronic lock as shown and described.

DESCRIPTION

FIG. 1 is a top, front, and right-side perspective view of an electronic lock showing our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The dashed broken lines depict portions of the electronic lock in which the design is embodied that form no part of the claimed design.

1 Claim, 6 Drawing Sheets
